UNITED STATES PATENT OFFICE.

JOHIEL JACKSON, OF COLUMBUS, WISCONSIN.

DESIGN FOR A SPOKE-HOLDER.

SPECIFICATION forming part of Design No. 35,244, dated October 29, 1901.

Application filed September 28, 1901. Serial No. 76,960. Term of patent 7 years.

To all whom it may concern:

Be it known that I, JOHIEL JACKSON, a citizen of the United States, and a resident of Columbus, in the county of Columbia and State 5 of Wisconsin, have invented and produced a new and original Design for a Spoke-Holder, of which the following is a full, clear, and exact description.

Reference is to be had to the accompanying 10 drawings, forming a part of this specification, in which similar characters of reference indicate corresponding parts in all the figures.

Figure 1 is a plan view of a spoke-holder, showing my design. Fig. 2 is a sectional side 15 elevation of the same on the line 2 2 of Fig. 3, and Fig. 3 is a transverse section of the same on the line 3 3 of Fig. 2.

The invention relates to devices for repairing broken spokes without resetting the tire.

The design in its entirety consists of an elongated top plate A, from one end and the sides of which depends a flange B, having spaced ends B' and B², projecting beyond the other end of the top plate, the end B' being beveled

at the outer face and the other end beveled at 25 the inner face, as plainly indicated in Fig. 1, and from the ends of the top plate A project upwardly the transversely-extending lugs C C', and from the center of the top plate projects upwardly the pin D, terminating in a 30 wedge D', the top edge of which extends longitudinally at right angles to the lugs C C'.

The leading feature of the design consists in the top plate, having the lugs, the depending flange open at the ends, and the pin on 35 the top plate and terminating in a wedge.

Having thus described my invention, I claim as new and desire to secure by Letters Patent—

The design for a spoke-holder as herein 40 shown and described.

In testimony whereof I have signed my name to this specification in the presence of two subscribing witnesses.

JOHIEL JACKSON.
